UNITED STATES PATENT OFFICE.

EDWARD J. Y. RUTHERFORD, OF LONDON, ENGLAND, ASSIGNOR TO NEW SYSTEM OIL BURNERS LIMITED, OF LONDON, ENGLAND.

LIQUID-FUEL BURNER.

Application filed April 20, 1922. Serial No. 555,773.

To all whom it may concern:

Be it known that I, EDWARD JAMES YOUNG RUTHERFORD, a subject of the King of Great Britain, and resident of London, England, have invented certain new and useful Improvements in Liquid-Fuel Burners, of which the following is a specification.

This invention has reference to liquid-fuel burners and has for object to provide an improved burner installation employing kerosene or other liquid hydrocarbon, especially intended for domestic purposes such as portable cooking stoves, heaters for installation in existing kitchen ranges and the like.

The apparatus is of the type in which a discharge of air or steam in proximity to the fuel nozzle, causing the fuel to flow by suction, atomizes and mixes with the fuel, the steam being generated in a coil heated by the flame from water supplied from a pressure tank or other source.

According to the present invention, the steam delivered to the atomizing nozzle is generated in duplex or multiple coils, rings or the like connected in parallel, the coils being also cross-connected, if desired, at certain points in their length and constituting a flash generator; by the expression "coils connected in parallel," I intend to cover two or more coils having a common connection at the supply point and being re-united at or before the point of delivery.

The atomizing burner is provided with regulating means at the tip of the jet, the latter being displaceable axially within the air or steam nozzle so that the discharge and suction may be regulated as required. The fuel sucked through the bore of the jet remains constantly in correct proportion to the atomizing discharge. Moreover, at starting, the opening of the nozzle may be increased so as to free the nozzle from any adherent solid deposit or liquid residues which would otherwise render the operation uncertain.

The invention is hereafter described with reference to the accompanying drawings, in which:—

Figure 1 is an elevation of an atomizing burner of the vertical type, mounted upon

a base containing fuel and water, the base being shown in part section. Figure 2 is a sectional elevation of the burner and its supply tubes.

Figure 3 is a detail of the three-way controlling valve.

Figure 4 shows a form of burner adapted for use in a horizontal position.

Figure 5 is a cross section on line 5—5 of Figure 4.

Figures 6, 7 and 8 are enlarged details of the three-way cock illustrated in Figure 4.

Referring to Figures 1 and 2, the base *a* comprises two chambers, of which the upper *a*² contains water and the lower *a*⁴ contains the fuel; means are provided at *a*³ and *a*⁵ for refilling the two chambers. A hand-pump *b* of any suitable kind delivers air under pressure into the chamber *a*².

The body *c* of the burner is mounted upon the base *a*, by screwing into a pipe *b*' extending vertically through the base, the top of the pipe presenting a conical seating, as indicated at *a*⁵. This burner-body encloses a fuel jet *d* which is bored throughout its length and connected to a pipe *d*' which passes down inside the pipe *b*' to a filter *b*² connected through holes *b*³ with the fuel chamber *a*². An external screw cap *b*⁴ fitting upon the projecting lower end of the pipe *b*' allows access to the filter *b*² and to the interior of the pipes *b*' *d*'.

The jet *d* screws from below into the body *c* and its upper end *2* is reduced in diameter to provide an annular space *3*, to which steam is supplied as hereafter described; the tip or extremity *4* of the jet is tapered to enter the burner orifice *c*'. In the construction shown, this orifice is formed in a thimble *c*² movable within a gland *c*³ in the burner body, and screwing upon the screw threaded portion of the jet *d*. Thus the position of the thimble is adjustable, for example by means of an external handle *c*⁴ whereby the thimble can be rotated through a portion of a revolution, the resulting axial travel varying the opening of the orifice *c*' in relation to the jet. A burner-cap *c*⁵ may be mounted upon the thimble to allow

thorough mixing of the fuel and steam before ignition in the atmosphere.

The annular space around the upper end of the jet connects with a steam generator *e*, comprising two vertical pipes or branches *e'* communicating at diametrically opposite points with the burner-body *c*, where they deliver steam through radial passages 5 into the annular space 3. The upper ends of these branch pipes *e'* connect with a tubular ring *e*² having two other branches *e*³ in a plane perpendicular to that of the first branches *e'* and connecting with an upper ring *e*⁴; the latter has two other branches *e*⁵ in the same vertical plane as the first pair *e'*, connecting with an outer ring *e*⁶ to which water is fed at two diametrically opposite points through a U-shaped connection 6 from a pipe *f* which extends down into the burner-body *c* and is connected by channels in the seating *a*⁶ with a pipe *f'* fitted with a 15 three-way valve *f*² whereby it communicates either through orifices 7 with the air-space in the top of the chamber *a'* or through a pipe *f*³ with the water-space in this chamber.

At starting, the air in the air-chamber *a'* under the pressure produced by the pump *b* is allowed to pass through the valve *f*² into the pipe *f* and thence through the steam generator *e* to the annular space 3 around the jet *d*. When the thimble *c*² is raised 25 by means of the handle *c*⁴ it affords an annular nozzle opening around the jet-tip 4 through which opening the air escapes, drawing up the fuel from the chamber *a*² by suction through the jet *d*. The fuel 30 atomized by the air-blast is then ignited above the burner orifice *c'*, and the steam generator *e* is thereby heated to full temperature.

As soon as the flame is ignited, the valve 40 *f*² is gradually rotated to reduce the air supply and admit water to the generator *e*; this water is forced up by the internal air-pressure in the chamber *a'* into the pipe *f* and generator *e*, producing steam pressure to 45 maintain the jet and flame in action. When regular action is obtained, the air-valve *f*² is turned to the working position, completely stopping the air-supply and allowing water to pass freely to the generator. In order to 50 extinguish the flame, the thimble *c*² is displaced to close the burner orifice *c'*, the steam then blowing back into the water tank and condensing therein.

Instead of using air for starting purposes, 55 a heating trough may be provided around the generator to contain asbestos or the like, which is saturated with methylated spirits in the known manner.

A choke tube *e*⁷ may be provided to 60 induce air and to shield the feed water heater *e*⁶ from direct contact with the flame; a flame spreader *e*⁸ mounted above the upper ring *e*⁴ may be domed as shown to extend down towards the centre of the generator *e*.

65 Figure 4 represents a second form of con-

struction which is intended more particularly for position where the flame is to be directed horizontally.

In this example, the burner *c* is adjustably mounted by means of a bracket *g*' upon a 70 column *g* and passes into a Venturi-tube *h*³. The column *g* is secured to the water tank *a'* and forms part of the air and water supply system as hereafter described.

The water tank *a'* is provided with a hand 75 pump *b*, and a filling orifice *a*⁸, as well as a pressure gauge 8 and release valve 9 if desired. The column *g* passes through the top of the reservoir, its lower end being preferably secured to the bottom but with 80 holes or ports *g*³ to allow access of water to the interior of the column; one or more holes *g*⁴ are also provided in the column near the top of the reservoir to admit air from the 85 space above the water level.

Upon the column there is secured the bracket *g*', which is adjustable as to height by means for example of a split collar 10 fitted with a bolt 11 and wing nut 12. The bracket is provided with two arms forming 90 a cross-member, one arm *g*² supporting the fuel tank *a*² and the other *g*⁵ carrying the burner *c*, the control lever *c*⁴, the steam generating coils *e* and the connecting pipes *d*' and *f*. 95

The feed pipe *d*' from the fuel tank is carried to the burner *c*, being connected preferably to the rear end of the hollow jet *d*, and comprising if desired means such as a coupling 13 to accommodate the slight movement of the jet *d*. The latter is reduced at its forward end 2 and coned at the extremity 4 as in the former construction, the pointed extremity entering the burner orifice *c'*. The jet is adjustable by means of the 105 external handle *c*⁴ connected to the jet by a peg and groove device 14 and secured to a nut *d*² which screws upon the exterior of the body *c*. A packing gland 15 is provided around the centre of the jet to prevent 110 leakage.

Fuel is delivered to the pipe *d*' through a regulating device. I prefer to arrange the tank *a*² in conjunction with a constant-level feed-bowl *a*⁶ supplied by the flow from the open mouth 16 of the inverted tank. The mouth may be fitted with a valve 17 which is held open in the normal position, but is closed automatically by a spring *a*⁷ as soon as the tank is raised for refilling or inspection. A needle valve or the like *a*⁸ may also be fitted for adjusting the flow of fuel. 115

The burner body *c* is held as shown in Figure 5, by the divided flange *h*⁴ of a Venturi-tube *h*³ carried by the bracket *g*'. This 125 tube-fitting has also a central external flange *h*' for attachment to the protecting plate *h* which covers the front of the grate or the like. From the lower front end of the Venturi-tube there projects a plate or jib *h*², 130

preferably of T-section, which serves as support for the steam generator *e*, the latter comprises a plurality of pipes, for example two, coiled helically upon a conical or other suitable pitch-surface and connected at the rear end to a pipe *e'* which extends to the burner and communicates with the annular space around the reduced forward end 2 of the jet *d*. At the front end of the steam 10 generator, the pipes are connected to a water pipe *f* which extends beneath the jib *h*² and communicates with the control cock *i*. The coils of the steam generator *e* may be cross-connected at points in their length if so 15 desired.

In the arrangement illustrated, the controlling cock *i* is located at the upper end of the column *g*, and the water pipe *f* is connected to the port *i'* (see Figure 7). The 20 other ports *i²* and *i³* of the cock communicate respectively the one with the interior of the column and thus through the holes *g⁴* with the air-space above the water in the tank, the other *i³* with a pipe *i⁴* extending down inside the column *g* to near the bottom of the tank. The cover-plate *i⁵* of the valve *i* (see Figure 8) has a recess or passage *i⁶* whereby the port *i'* can be connected with either or both of the ports *i²* *i³*. 25

In the starting position shown in Figure 6, air under pressure is passed through the ports *i²* *i'* to the pipe *f* and vapourizer *e* the resulting suction upon the jet *d* producing a flow of fuel which is atomized by the 30 air-blast and may be ignited at the mouth of the Venturi-tube *h*³. The control valve is then rotated to bring the port *i³* gradually into action, thereby delivering water through the pipes *i⁴* and *f* to the generator 35 *e*. As soon as sufficient heat is attained, the control valve may be turned to the normal running position, when the air supply through the port *i²* is shut off and only water is delivered to the steam generator. 40

The flame can then be regulated by means of the handle *c*⁴ which adjusts the opening of the air-nozzle and therefore also the flow of fuel in a corresponding proportion.

It will be understood that instead of employing a separate water tank, any ordinary water-main or service pipe may be used to supply water to the steam generating coils; air for starting purposes may 50 then be provided by any suitable pumping means or storage vessel, or a heating trough may be employed for generating steam in the first place.

Having thus described my invention, 55 what I claim is:

1. A liquid fuel burner, comprising a nozzle, a fuel jet within said nozzle, suction controlled means for supplying fuel to said jet, and a flash generator adapted to 60 be heated by the burner, said generator

having a plurality of symmetrically disposed branches of equal length cross-connected at points in their length and being adapted to supply steam to said nozzle so as to produce suction around said fuel jet. 70

2. A liquid fuel burner, comprising a base, fuel and water reservoirs in said base, means for compressing air above the water in one of said reservoirs, a burner-body mounted upon said base, a flash generator 75 mounted above said burner-body, said generator affording a plurality of equal paths for balancing the flow of liquid, a fuel jet within said body, means for applying fuel from the other of said reservoirs by suction to said fuel jet, a burner nozzle mounted in said body and surrounding said jet, said jet and nozzle being arranged coaxially and displaceable in relation to one another, said jet regulating the opening through said nozzle by such displacement, means for controlling the supply of air and of water from the first of said reservoirs to said flash generator, and means for delivering fluid from said generator to said nozzle around said fuel jet. 80

3. A liquid fuel burner, comprising a nozzle, a fuel jet arranged axially within said nozzle, said jet being displaceable relatively to said nozzle and regulating the opening therethrough, and a flash generator adapted to be heated by the burner, said generator including coaxially disposed annular tubes, symmetrically disposed connections between successive pairs of said tubes, connections to one of said annular tubes from a water supply, and connections from another of said annular tubes to said nozzle around said jet. 90

4. A liquid fuel burner, comprising a base, fuel and water reservoirs in said base, means for compressing air above the water in one of said reservoirs, a tube extending down through said reservoirs and communicating with the other of said reservoirs, a burner-body, screwing into the upper end of said tube, a fuel jet within said body, a pipe connecting the bore of said jet with the fuel reservoir, a burner-nozzle rotatably mounted in said burner-body, means for displacing said nozzle in relation to said fuel jet, said nozzle having a burner orifice aligned with said jet, the opening of said burner orifice being regulated by the relative displacement between said nozzle and jet, a flash generator mounted above said burner-body, said generator affording a plurality of equal paths for balancing the flow of liquid, and adapted to be heated by the burner, means for controlling the supply of air and of water from the first of said reservoirs to said flash generator, and means for delivering fluid from said generator to said nozzle around said fuel jet. 110

5. In a liquid fuel burner, the combination 115

tion with a fuel nozzle and an atomizing nozzle, by which steam is delivered in proximity to the fuel nozzle, to produce suction of fuel through said fuel nozzle, of multiple coils of equal length and dimensions connected in parallel to constitute a flash generator.

6. In a liquid fuel burner, the combination with a fuel nozzle and an atomizing nozzle, by which steam is delivered in proximity to the fuel nozzle, of multiple coils of equal length and dimensions connected in parallel and also cross-connected at points in their length to constitute a flash generator.

7. In a liquid fuel burner, the combination with a fuel nozzle and an atomizing nozzle, by which steam is delivered in proximity to the fuel nozzle, of a plurality of coils extending and interconnected symmetrically to provide balanced paths for the flow of fluid, said coils constituting a flash generator.

8. In a liquid fuel burner, the combination with a fuel nozzle and an atomizing

nozzle by which steam is delivered in proximity to the fuel nozzle, of a flash generator comprising coaxially disposed annular tubes, symmetrically disposed connections between successive pairs of said tubes, a flame spreader integral with one of said annular tubes, connection to one of said tubes from a water supply, and connections from another of said tubes to said atomizing nozzle.

9. In a liquid fuel burner, the combination with a fuel nozzle and an atomizing nozzle by which steam is delivered in proximity to the fuel nozzle, of a flash generator comprising a flame spreader and vaporizing means integral with said flame spreader said vaporizing means including a plurality of fluid passages arranged in parallel and interconnected at points in their length to afford a balancing action and prevent surging of the steam supply to said atomizing nozzle.

In testimony whereof I hereunto affix my signature.

EDWARD J. Y. RUTHERFORD.
